CONVERSION OF CARBONACEOUS MATERIALS INTO FUELS OF RELATIVELY LOW BOILING POINT RANGE

Application filed November 20, 1928, Serial No. 320,765, and in Germany December 17, 1927.

The present invention relates to the conversion of carbonaceous materials into fuels of comparatively low boiling point range.

The conversion of various kinds of coal into hydrocarbons by first treating them with hydrogen at elevated temperatures and high pressures, and then subjecting the products so obtained to the same treatment but in the presence of catalytic substances, has already been described. It has further been suggested, that especially the middle oils can be advantageously converted into benzine by the employment of catalytic substances because by the use of the said oils the activity of the latter is maintained for a long time. It is important, however, that the middle oils to be treated should be free from high molecular carbon compounds since these may choke the catalysts and render them inactive. Such compounds are generally still present in the crude products obtained directly from the liquefaction of coal.

I have now found that carbonaceous materials such as substances of the nature of coal, tars, mineral oils and the like are converted into liquid fuels of relatively low boiling point range such as benzine, middle oils and illuminating oils by destructive hydrogenation (which process, as is known, is effected at temperatures between 300° and 700° C. and under elevated pressures of more than 20 atmospheres, in the presence of hydrogen or gases containing or supplying the same, for example water vapor, easily decomposable hydrocarbons or hydrogen chloride, and preferably in the presence of catalytic substances) in more than one stage, by removing to a considerable extent the carbonaceous substances of high molecular weight, contained in the vaporous products, which disturb the further refining from the vaporous products obtained in the first stage, or if desired also in later stages, before subjecting the latter to a treatment in a further stage, but without condensing appreciable quantities of other substances suitable for further refining. As examples of such carbonaceous substances of high molecular weight disturbing refining may be mentioned for example heavy oils of high boiling point range, asphaltic and

pitchy substances, phenols of high boiling point and the like. The injurious substances should at the most be present in only such small quantities that any harmful influence on the catalytic substance employed in the second or later stages is avoided. The permissible concentration of these harmful substances depends in particular on the porosity of the catalysts employed in the second and later stages.

The process may be carried out for example by removing the injurious substances from the vapors by passing them over solid masses, for example absorptive masses such as active carbon, active silica and the like, by which the injurious substances are retained. A fractionating device may also be attached behind the first reaction chamber, and herein the high molecular carbonaceous substances, such for example as heavy oils, are removed, so that they do not come into contact with the catalysts employed in a later stage, while the fractions to be further treated pass through uncondensed. Liquid absorption agents may also be employed.

The process may also be carried out by making the linear velocity of the current of the substance to be converted in the first stage, or, if desired, also in the later stages, so small, that the high molecular carbonaceous products are decomposed before entering the second or later stages. In order to be able to decrease the linear velocity of the current to a great extent, correspondingly vigorously stirring must be carried on in these prior stages.

It is preferable to operate in such a manner that the products to be treated are treated in the first stage in the liquid phase at such a temperature that the injurious products, which for example would cause injury to the catalysts in a later stage, are not evaporated.

In the different stages of the process in accordance with the present invention, suitable catalytic substances are employed, for example, when operating in the liquid phase, it is advantageous to employ them in a form very finely distributed in the liquid. In this case it may in some cases be advantageous

in order to attain a high effect to treat the catalysts or the liquids containing the same in high-speed mills, for example in colloid mills. It is advisable to take care that substances which give rise to injurious reactions, such as deposition of carbon, formation of methane and the like, are excluded from the parts of the apparatus which come into contact with the hot reacting materials.

- 10 The initial materials in accordance with the present invention may be wholly or partially worked up into benzines. At appropriate places in the apparatus oils may be drawn off, which may be used for example 15 as scrubbing oils for pasting up coaly initial materials, or as initial material in the manufacture of lubricating oils.

Catalysts particularly suitable for the process of the present invention, both for the 20 process of destructive hydrogenation proper and for the conversion of the noxious substances of high molecular weight, are those immune against poisoning by sulfur or its compounds. As examples of such catalysts 25 may be mentioned catalysts comprising compounds containing sulfur in combination, for example metallic sulfids, in particular the heavy metal sulfids and more especially those of the iron group, either 30 alone or as mixtures with one another or with metals, metalloids, active charcoal, coke or the like or with oxids, hydroxids, or carbonates, or with other materials of a catalytic or of inert nature. The sulfur may also be 35 combined with the catalyst by adding sulfites or sulfates thereto or by the addition of sulfur to metals or oxids. A very suitable catalyst may be obtained by treating iron with hydrogen sulfid at an elevated temperature. 40 Particularly suitable catalysts of this class are for example cobalt sulfid, iron sulfid, zinc sulfid, nickel sulfid, manganese sulfid and the like or mixtures thereof, for example, mixtures of cobalt sulfid with nickel sulfid or 45 of cobalt sulfid with manganese sulfid, or of cobalt sulfid mixed with iron sulfid, or with zinc sulfid or with aluminum sulfid, with or without an addition of inert substances. Catalysts consisting of or containing 50 molybdenum, chromium, uranium or tungsten or the compounds thereof or mixtures of those substances are also particularly suitable. As examples of this type of catalyst may be mentioned molybdic acid 55 or ammonium molybdate, tungsten sulfid, tungstic acid, uranium oxid, chromium hydroxid and chromic acid. Mixtures of chromium or tungsten with other catalysts such as with cobalt, nickel or iron may also be 60 employed. Activation of the catalysts or the addition of substances increasing their mechanical strength may also be of advantage, this being effective for example with substances having a basic action such as 65 potassium carbonate, aluminium hydroxid

or calcium carbonate. Carriers such as lumps of aluminium silicate may also be employed with advantage. As further catalysts may be mentioned oxidic catalysts comprising zinc oxid, chromium oxid or manganese oxid 70 or mixtures of these, if desired, with an addition of a compound containing fixed nitrogen, such as ammonium sulfid or such nitrids as are comparatively stable against the action of water, for example silicon nitrid or titanium nitrid. These said oxidic catalysts may be employed in conjunction with other substances such as lumps of fire-clay, quartz, asbestos, pumice, coke, active charcoal, metals, in particular heavy metals, metalloids, 80 oxids, sulfids, carbids, and the like and mixtures thereof with the said substances. As still further examples of suitable catalysts may be mentioned such containing at least one of the elements silver, copper, cadmium, 85 lead, bismuth, tin in the form of its compounds, further the difficultly reducible metal oxids or carbonates, such as magnesia, lithium carbonate, boric acid, alumina, the rare earths, including the difficultly reducible 90 oxids of metals from the 4th group of the periodic system, or the oxids of zinc, manganese or vanadium. The catalysts may contain several of these substances or also other substances, for example metals from the 8th 95 group of the periodic system, such as iron. As specific examples of these catalysts may be mentioned such obtained by impregnating porous refractory materials with solution of lead nitrate, or of stannous chlorid, silver 100 nitrate or of copper hydroxid, either alone or in admixture with compounds of iron, cobalt and the like. Further may be mentioned catalysts containing the oxids of silver or of titanium, or lithium carbonate, magnesite, 105 manganese oxid, silver borate or mixtures of copper oxid with cerous oxid or of silver with cobalt oxid and the like, and also porous refractory masses coated with vanadium oxid or thorium oxid or with a mixture of 110 compounds of uranium and zinc or of silver and tungsten. These latter compounds may also be employed as such without application to the said porous materials. As further suitable catalysts may be mentioned catalysts containing active charcoal or the metalloids boron, silicon, phosphorus, arsenic, 115 selenium, tellurium or the compounds thereof or halogens. These metalloids may advantageously be employed together with elements from the 2nd to the 8th group of the periodic system, in particular such selected from the 6th group of the periodic system. The catalysts may for example contain the 120 following acids or their salts, namely phosphoric acid, arsenious acid, silicic acid, boric acid, hydrofluoric acid, hydrochloric acid, selenious acid and the like. As specific examples may be mentioned silicon carbide, 125 alder-wood charcoal which has been glowed

at 800° C. and impregnated with phosphoric acid, calcium phosphate, molybdenum phosphate, tungsten phosphate, iron phosphate, aluminium phosphate, arsenious acid together with molybdenum or tungsten, silicids, for example iron silicid containing 15 per cent of silicon, active silica, hydrosilicates, borids such as titanium borid or iron borid, calcium fluorid, molybdenum with 10 per cent of aluminium chlorid, molybdenum with 10 per cent of cadmium chlorid, molybdc acid with sodium selenite. Compounds containing fixed nitrogen may also be employed with advantage in the reaction. Thus ammonia or its salts, for example, ammonium sulfid and in some cases organic compounds of nitrogen may also be advantageous. Such nitrids as are fairly stable against the action of water have been found to give particularly good results. As further examples of suitable catalysts may be mentioned, such containing one or more elements from the *a* (4th to the 8th group of the periodic system, in particular such from the 6th group of the periodic system and more particularly molybdenum) together with *b* (small amounts of other elements from the 2nd to the 7th group of the periodic system or copper or gold or the compounds thereof). The elements from the 2nd and 3rd group may, however, also be employed in large amounts. Thus mixtures containing molecular proportions of molybdc acid with magnesia or with copper or with aluminium hydroxid, or mixtures of tungstic acid with zinc oxid or of vanadium oxid with magnesia furnish good results. Excellent catalysts are further molybdc acid with about 10 per cent of chromium oxid or of vanadium oxid, molybdc acid with about 10 per cent of uranium oxid or of thorium oxid or of manganous oxid, further tungstic acid containing about 10 per cent of chromium oxid or of a mixture of uranium oxid, cobalt and a small amount of chromium oxid. Again another very suitable class of catalysts is formed by the noble metals or lead or tin or compounds thereof on carriers, in particular on magnesia or magnesite or chromium oxid. As examples of this class of catalyst may be mentioned ruthenium, palladium, platinum, gold, lead or tin or magnesia or magnesite or platinum or gold or chromium oxid. Catalysts containing small amounts of silver or of mixtures of copper with zinc or with cadmium in a free state or in chemical combination and preferably also boron or aluminium or silicon or titanium, or vanadium, or tantalum or chromium or molybdenum or tungsten or cobalt in a free or combined state or mixtures of these are also very suitable. Examples of such catalysts are tantalic acid containing 10 per cent of silver, molybdc acid containing 10 per cent of silver or silica containing 10 per cent of a mixture of cop-

per and zinc. Again another class of catalysts consists of refractory metals or alloys on which small amounts of solid oxids of elements having a catalytic action from the 3rd to the 7th group of the periodic system have been deposited. The said metals or their alloys are preferably employed in an etched condition and preferably acidified solutions of salts of the said oxids are employed as the etching agent. Such catalysts as are employed in the production of methanol from hydrogen and oxids of carbon are also very suitable.

The process is preferably carried out at elevated pressure such as about 20, 50, 100 or 150 atmospheres, although when a very thorough reaction is desired, higher pressures such as 200, 500, 1000 or even more atmospheres may be employed. On the other hand it may in some cases be of advantage to carry out the process under atmospheric pressure.

The temperatures employed should always be above the decomposition point of the initial material, and usually range between about 300 and 700° C.

The accompanying drawing shows in a diagrammatic manner an apparatus, partly in section, in which the process according to the present invention may be carried out.

A hydrocarbon oil to be converted is supplied at *s* and pumped by means of pump *v* into the heating coil *g*. Hydrogen is simultaneously supplied at *t* and pumped by means of pump *u* into the same heating coil *g*. The hot mixture of hydrocarbon oil and hydrogen is supplied at *a* into the first hydrogenating vessel *b* which is filled with a catalyst prepared from molybdc acid, chromic acid and manganese carbonate and which is kept at a temperature of about 420° C. The vaporous mixture formed is led together with the excess of hydrogen without releasing the pressure through the pipe *c* into a condensing apparatus *d* filled with an adsorptive mass, such as active carbon and provided with a cooling coil *w* through which water is passed. In this condensing apparatus *d* the parts boiling above 350° C. are substantially condensed and are returned to the reaction vessel *b*. The gases and vapors not condensed pass through pipe *e* into a heating coil *m* and from thence into a second hydrogenating vessel *f* which is filled with a catalyst prepared from molybdc acid, zinc oxide and manganese oxide and which is kept at a temperature of about 470° C. From the reaction vessel *f* the vaporous mixture formed passes by way of the pipe *g* to a condenser *h*. The condenser liquids are gathered in the vessel *i* and drawn off at *o*. The uncondensed parts are drawn off at *l*. 60 per cent of the liquid products boil up to 200° C., the rest up to 325° C. Residues formed in the hydrogenating vessel *b* are drawn off at *p*. By this manner of working the activity of the catalyst in *f* is pre-

served for a long time whereas the catalyst is soon rendered inactive when the parts boiling above 350° C. of the vaporous products issuing from *b* are not removed at *d*.

5 The following examples will further illustrate the nature of the invention but the invention is not restricted thereto. The parts are by weight.

10 *Example 1*

Tar, obtained by destructive hydrogenation or low-temperature distillation of brown coal, of which about 60 to 70 per cent boils above 350° C. is treated in the liquid phase 15 with hydrogen at 420° C. and under 200 atmospheres pressure. The reaction product obtained is passed in the form of vapor first over a catalytic substance comprising molybdenum and zinc at the same temperature and 20 then at 460° C. over a catalytic substance consisting of trioxides of molybdenum and chromium. A product containing 80 to 90 per cent of benzine, free from phenol and 25 consisting mainly of saturated hydrocarbons is thus obtained in a continuous operation.

By the employment of the pre-arranged catalytic substance comprising molybdenum and zinc the initial high yield is maintained during the continuous operation. Instead 30 of the said catalytic substance, active carbon or other absorptive agents may be employed which are renewed either continuously or from time to time.

35 *Example 2*

50 parts of finely ground pit coal made up into a paste with 50 parts of an oil residue, obtained in a destructive hydrogenation process, are treated at 450° C. and under a 40 pressure of 200 atmospheres with hydrogen in the presence of a catalyst containing molybdenum and zinc. Part of the said oil residue is converted into benzine and middle oil and issues as such from the apparatus. 45 The residual part of higher boiling point is separated from the solid residues and is treated in the liquid phase at a temperature of 400° to 440° C. and under a pressure of 200 atmospheres with hydrogen in the presence of 50 a catalyst containing molybdenum, manganese and chromium. The vaporous products, issuing from the reaction vessel are freed from oils of high boiling point range, which would have an undesirable influence in the 55 further stages of the process, by being passed over active charcoal and are then treated with hydrogen at 460° C. and under a pressure of 200 atmospheres in the presence of a catalyst containing molybdenum, chromium and aluminium.

A good yield of a product of the nature of benzine is obtained which has no tendency to knocking when employed as a fuel for internal combustion engines and which may also 65 be employed with advantage as an addition

to liquid fuels which have a tendency to knock.

Example 3

Brown coal producer tar is passed together with hydrogen at 420° C. and under a pressure of 200 atmospheres over a catalyst produced from molybdenic oxide, chromic oxide and manganous carbonate. The vaporous mixture thus obtained is passed without releasing the pressure into a condensing vessel, the temperature of which is so adjusted that those constituents which under normal pressure boil above about 350° C. are separated off. These may be run off from the reaction vessel and amount to about 10 per cent by weight of the vaporous products present in all. The residual vapors are passed at a temperature of 470° C. over a catalyst consisting of molybdenic oxide, zinc oxide and magnesium oxide. In this manner a product is obtained, 80 per cent of which distil at temperatures below 200° C., whereas the remainder passes over at temperatures up to about 325° C.

85 The activity of the second catalyst is maintained uniformly excellent for a long time according to this manner of working, whereas, without a preliminary separation of the constituents boiling above 350° C., the activity of the catalyst soon decreases on account of condensations on the surface thereof. The rate of flow of the vaporous mixture which in the first reaction vessel is usually 90 adjusted at about 1.5 to 2 centimeters per second, is preferably lowered in the stripper, for example by suitably widening the cross-sectional area of this part; in the second reaction vessel the rate of flow of the gases 95 may be increased to about 4 to 5 centimeters per second.

100 What I claim is:—

1. In the conversion of carbonaceous materials into liquid fuels of relatively low boiling point range by destructive hydrogenation at a temperature between 300° and 700° C. 110 and under a pressure of more than 20 atmospheres in more than one stage in the presence of catalytic substances, the step of removing substantially all the carbonaceous substances of high molecular weight, which disturb the further conversion, contained in the vaporous products derived from the first stage of the process, without appreciably depreciating the quantity of substances suitable for further conversion prior to a further destructive hydrogenation of said vaporous products with a catalyst subject to clogging by said substances of high molecular weight.

115 2. In the conversion of carbonaceous materials into liquid fuels of relatively low boiling point range by destructive hydrogenation at a temperature between 300° and 700° C. 125 and under a pressure of more than 20 atmospheres in more than one stage, the first stage being carried out in the liquid 130

state, and in the presence of catalytic substances the step of removing substantially all the carbonaceous substances of high molecular weight, which disturb the further conversion, contained in the vaporous products obtained in the first stage of the process, without appreciably depreciating the quantity of substances suitable for further conversion prior to a further destructive hydrogenation 5 of said vaporous products with a catalyst subject to clogging by said substances of high molecular weight.

3. In the conversion of carbonaceous materials into liquid fuels of relatively low boiling point range by destructive hydrogenation at a temperature between 300° and 700° C. and under a pressure of more than 20 atmospheres in more than one stage in the presence of catalytic substances the step of 10 removing substantially all the carbonaceous substances of high molecular weight, which disturb the further conversion, contained in the vaporous products obtained prior to the last stage of the process without appreciably depreciating the quantity of substances suitable for further conversion prior to a further 15 destructive hydrogenation of said vaporous products in the last stage of the process with a catalyst subject to clogging by said substances of high molecular weight.

4. In the conversion of carbonaceous materials into liquid fuels of relatively low boiling point range by destructive hydrogenation at a temperature between 300° and 35 700° C. and under a pressure of more than 20 atmospheres in more than one stage, at least the first stage being carried out in the liquid state, and in the presence of catalytic substances, the step of removing substantially 40 all the carbonaceous substances of high molecular weight, which disturb the further conversion, contained in the vaporous products obtained prior to the last stage of the process, without appreciably depreciating the quantities 45 of substances suitable for further conversion prior to a further destructive hydrogenation of said vaporous products with a catalyst subject to clogging by said substances of high molecular weight.

5. In the conversion of carbonaceous materials into liquid fuels of relatively low boiling point range by destructive hydrogenation at a temperature between 300° and 700° C. and under a pressure of more than 20 atmospheres in more than one stage, and in the presence of a catalyst immune from poisoning by sulfur, the step of removing substantially 55 all the carbonaceous substances of high molecular weight, which disturb the further conversion, contained in the vaporous products, derived from the first stage of the process, without appreciably depreciating the quantity of substances suitable for further conversion prior to a further destructive hydrogenation of said vaporous products with a catalyst subject to clogging by said substances of high molecular weight.

catalyst subject to clogging by said substances of high molecular weight.

6. In the conversion of carbonaceous materials into liquid fuels of relatively low boiling point range by destructive hydrogenation at a temperature between 300° and 700° C. and under a pressure of more than 20 atmospheres in more than one stage, the first stage being carried out in the liquid state, and in the presence of a catalyst immune from poisoning by sulfur, the step of removing substantially all the carbonaceous substances of high molecular weight which disturb the further conversion, contained in the vaporous products, issuing from the first stage of the process, without appreciably depreciating the quantity of substances suitable for further conversion prior to a further destructive hydrogenation of said vaporous products with a catalyst subject to clogging by said substances of high molecular weight.

7. In the conversion of carbonaceous materials into liquid fuels of relatively low boiling point range by destructive hydrogenation at a temperature between 300° and 700° C. and under a pressure of more than 20 atmospheres in more than one stage, and in the presence of a catalyst immune from poisoning by sulfur, the step of removing substantially all the carbonaceous substances of high molecular weight, which disturb the further conversion, contained in the vaporous products obtained prior to the last stage of the process, without appreciably depreciating the quantities of substances suitable for further conversion prior to a further destructive hydrogenation of said vaporous products in the last stage of the process with a catalyst subject to clogging by said substances of high molecular weight.

8. In the conversion of carbonaceous materials into liquid fuels of relatively low boiling point range by destructive hydrogenation at a temperature between 300° and 700° C. and under a pressure of more than 20 atmospheres in more than one stage, at least the first stage being carried out in the liquid state, and in the presence of a catalyst immune from poisoning by sulfur, the step of removing substantially all the carbonaceous substances of high molecular weight, which disturb the further conversion, contained in the vaporous products obtained prior to the last stage of the process, without appreciably depreciating the quantity of substances suitable for further conversion prior to a further destructive hydrogenation of said vaporous products with a catalyst subject to clogging by said substances of high molecular weight.

9. In the conversion of carbonaceous materials into liquid fuels of relatively low boiling point range by destructive hydrogenation at a temperature between 300° and 700° C. and under a pressure of more than 20 atmospheres in more than one stage in the presence

of catalytic substances, the step of removing the carbonaceous substances of high molecular weight, which disturb the further conversion, from the vaporous products issuing from the first stage of the process by means of an adsorbent, without condensing appreciable quantities of substances suitable for further conversion prior to a further destructive hydrogenation.

10. 10. In the conversion of carbonaceous materials into liquid fuels of relatively low boiling point range by destructive hydrogenation at a temperature between 300° and 700° C. and under a pressure of more than 20 atmospheres in more than one stage, at least the first stage being carried out in the liquid state, and in the presence of catalytic substances, the step of removing the carbonaceous substances of high molecular weight, which disturb the further conversion, from the vaporous products issuing from the first stage of the process by means of an adsorbent, without condensing appreciable quantities of substances suitable for further conversion prior to a further destructive hydrogenation.

11. 11. In the conversion of carbonaceous materials into liquid fuels of relatively low boiling point range by destructive hydrogenation at a temperature between 300° and 700° C. and under a pressure of more than 20 atmospheres in more than one stage in the presence of catalytic substances, the step of removing the carbonaceous substances of high molecular weight, which disturb the further conversion, from the vaporous products obtained prior to the last stage of the process by means of an adsorbent, without condensing appreciable quantities of substances suitable for further conversion prior to a further destructive hydrogenation in the last stage of the process.

12. 12. In the conversion of carbonaceous materials into liquid fuels of relatively low boiling point range by destructive hydrogenation at a temperature between 300° and 700° C. and under a pressure of more than 20 atmospheres in more than one stage, at least the first stage being carried out in the liquid state, and in the presence of catalytic substances, the step of removing the carbonaceous substances of high molecular weight, which disturb the further conversion, from the vaporous products obtained prior to the last stage of the process by means of an adsorbent, without condensing appreciable quantities of substances suitable for further conversion prior to a further destructive hydrogenation in the last stage of the process.

13. 13. The process for the conversion of pit coal into liquid fuels of comparatively low boiling point by destructive hydrogenation in more than one stage which comprises making up the said initial material into a paste with oil, treating it at about 450° C. and under a pressure of about 200 atmospheres

with hydrogen in the presence of a catalyst containing molybdenum and zinc, freeing the vaporous products issuing from the reaction vessel from the carbonaceous substances of high molecular weight, which have a tendency to choke the catalysts in the further stages of the conversion, by passing the vapors over active charcoal, and then treating the vapors issuing from the said treatment with hydrogen under a pressure of 200 atmospheres in the presence of a catalyst containing molybdenum, chromium and aluminium.

In testimony whereof I have hereunto set my hand.
